(No Model.)

E. MYERS.
VENEER SAWING MACHINE.

No. 550,637.

Patented Dec. 3, 1895.

FIG. I.

FIG.2.

FIG. 4.

FIG. 5.

Inventor

Edward Myers
By Geo. Murray Atty

UNITED STATES PATENT OFFICE.

EDWARD MYERS, OF CINCINNATI, OHIO.

VENEER-SAWING MACHINE.

SPECIFICATION forming part of Letters Patent No. 550,637, dated December 3, 1895.

Application filed April 1, 1895. Serial No. 543,944. (No model.)

To all whom it may concern:

Be it known that I, EDWARD MYERS, a citizen of the United States, and a resident of Cincinnati, in the county of Hamilton and 5 State of Ohio, have invented certain new and useful Improvements in Veneer-Sawing Machines, of which the following is a specification.

My invention relates to machines for sawing veneers. Its objects are to provide means to automatically offset the stay-log at the completion of its forward movement and automatically return it to the same position when the carriage is gigged back and started 10 to make a new cut, and also to provide means to rapidly carry the stay-log back for removing the remnant of the flitch and supplying a new one. These objects I attain by the means illustrated in the accompanying drawings, in 15 connection with which the invention will be 20 first fully described, and then particularly referred to and pointed out in the claims.

Referring to the drawings, in which like parts are indicated by similar reference-letters wherever they occur throughout the various views, Figure 1 is a rear elevation of so much of a veneer-sawing machine as is necessary to illustrate my invention. Fig. 2 is a detailed view, upon an enlarged scale, of the 25 means for feeding the stay-log and offsetting the same. Fig. 3 is a detail showing in plan view the means for rapidly backing the stay-log preparatory to supplying it with the flitch to be operated upon. Fig. 4 is a detailed 30 view, in edge elevation, of the offset mechanism shown in Fig. 2. Fig. 5 is a detail in plan view or top elevation of the means for actuating the feed-screw to offset the stay-log and to bring it back to its position.

40 The husk or frame of the machine A, with its slides or track, the carriage and stay-log B, and the means for driving the carriage, feeding the stay-log forward to take a new bite on the flitch, and for carrying the stay-log back, as illustrated particularly in Fig. 1, 45 are of ordinary construction, and, as formerly used, may be briefly described as follows:

Journalized in standards *a* at each end of the carriage are shafts carrying sprocket-wheels *C*, two sprocket-wheels being fixed upon each shaft. A sprocket-chain *c* passes over the front sprocket-wheels, and two chains

c' pass over the rear sprocket-wheels and sprocket-wheels *D*, which are keyed upon the end of the feed-screws *d*, which are journaled 55 in plain bearings.

In my improvement the bearings of the shafts are exteriorly-screw-threaded sleeves *d'*, which engage interiorly-screw-threaded boxes *d²*, secured to the insides of the up-60 rights *a*. The feed-screws *d* are held against longitudinal movement by collars abutting against the inner ends of the sleeves *d'* and jam-nuts upon the outer ends of the screw-shaft journals, which bear against the hub of 65 the sprocket-wheels *D*. The sleeves *d'* have extending from them crank-arms *d⁴*, which when turned in one direction or the other give a limited movement to the feed-screws and, of course, to the stay-log *B*, as the feed-70 screws are tapped through nuts *b*, which are secured to the ends of the stay-log.

To the back of the frame *A* is secured a rack *E*, which engages a pinion *e*, which has a band-wheel *e²* secured to it. Both are journaled upon a stud-bolt *e'*, which projects rearwardly from the base of the carriage or stay-log *B*. A belt passes around the pulley *e²*, and also around a pulley *e³*, which is journaled upon a stud-bolt *e⁴*, secured to the stay-log or 80 carriage. The stud-bolts are braced at their outer ends by a bar *e⁷*, the perforated ends of which pass over the ends of the stud-bolts and are secured in place by nuts, which hold the pulleys and pinions in position. 85

To the outer end of the pulley *e³* is secured a crank-arm *e⁵*, the lower end of which passes through a slot in the central coupling *f* of the rod *F*, the opposite ends of which are coupled to the crank-arms *d⁴*, which project down from 90 the sleeve *d'*. The belt *e* is secured by screws to the pulley *e³*, and the belt is united by a coupling-rod *e⁸*, by which the tension of the belt over the pulley *e²* may be regulated so as to allow the pulley to slip within the belt 95 when the rotation of the pulley *e³* is stopped by either one of the arms *d⁴* coming in contact with the end of the carriage or stay-log. To prevent jar and limit the movement of these arms, a buffer *d⁷* is secured in a lug projecting 100 laterally from the lever-arms *d⁴*.

It will be seen that the device for offsetting the stay-log in no way interferes with the old and well-known means of operating the feed-

screws for moving the stay-log transversely upon the carriage by means of moving the sprocket-chain *c* and that after the stay-log is drawn back and the carriage has moved 5 back far enough to bring the flitch some little distance back of the saw and the carriage again started forward to bring the stay-log up to the same position it occupied before the last cut was made the operator may, by 10 moving the feed-chain *c*, adjust the carriage forward against the indicator-roller until the finger of the indicator points to the index-stop, which indicates the thickness of the veneer to be severed from the flitch. The indicator, which is attached to the upright post 15 near the starting-lever and in full view of the operator and which is figured for different thicknesses and provided with an adjustable stop, is not shown herein, as it forms no part 20 of the present invention.

As before stated, the stay-log, after the flitches secured upon it have been exhausted, is moved back to receive new flitches by means of the feed-chain *c*, operated by hand, which 25 is a slow operation. I have provided means actuated by the customary feed mechanism by which the stay-log is rapidly moved back to receive new flitches without materially changing any parts of the feed mechanism. 30 My improvements may therefore be readily applied to any of the veneer-mills now in common use at little expense and without changing materially any of the parts of the well-known mill, and when applied will greatly 35 increase its capacity.

Referring to Figs. 1 and 3, I will first describe the arrangement for feeding the stay-log longitudinally on its carriage back and forth in the operation of sawing, to which no 40 claim is made, and then my improvement to be actuated by the feed-driving mechanism to carry the stay-log back preparatory to removing the exhausted flitch or flitches and supplying it with a new one to be operated 45 upon.

The feed is mounted in an iron frame *G*, secured to the rear side of the machine, and is composed of the paper and iron friction-wheels driven by a counter-shaft. (Not 50 shown.)

H is the shaft which passes under the carriage and which has a bull-wheel secured upon its inner end to engage a rack by which the carriage is fed forward when the friction-wheel *G'* is driven in one direction and gigged back when the wheel *G'* is driven in the opposite direction. The shaft *H* is mounted in movable bearings, the movement of the shaft being controlled by a lever within convenient 55 reach of the operator on the front side of the machine. The shaft *H* and its connections and the controlling-lever are not shown, as they differ in no respect from devices now in common use. The only purpose of this is to 60 bring the friction-wheel *G'* against the friction-pulley *I* to drive the carriage in one direction, against the friction-wheel *J* to drive 65

the shaft *H* in the opposite direction, or to throw the friction-wheel *G'* to its central position, as shown in Fig. 3, to stop the carriage. 70

The shafts upon which the pulleys *I* and *J* are secured revolve all the time, one, *i*, being driven by a straight belt passing over a pulley (not shown) secured upon the extended 75 end of the shaft and the other by a cross-belt passing over the cone-pulley *j*, secured upon the shaft *j'*, which carries the friction-pulley *J* from the counter-shaft pulleys, so that they revolve in opposite directions. 80 Upon one of these shafts *i* is secured another friction-wheel *i'*, which is directly below a friction-wheel *K*. The friction-wheel *K* is journaled in a box *k*, which box is suspended at the end of a link or arm *k'*. The 85 opposite end of the link is journaled upon a short shaft in the end of the crank-arm *k''*, which crank-arm is secured upon a shaft *K'*, which has its bearings in the uprights *a* at the rear end of the carriage. Upon the forward end of the shaft *K'* is secured a wheel *k''*, by which the shaft *K'* is rocked to throw the friction-wheel *K* up to the position shown in the drawings, which position it occupies while the flitches upon the stay-log are being 95 fed to the saw. Upon the inner end of the shaft upon which the pulley *K* is secured is secured a pinion *k⁴*, which meshes with the gear-wheel *d⁶*, which is secured upon the rear feed-screw *d*, the link *k'* and the crank-arm 100 *k''* keeping the pinion and gear-wheel in mesh when in either the upper or lower position. When the flitch is exhausted and it is desirable to supply a new one, the carriage is carried back to the position shown in Figs. 1 and 105 3 and the shaft *K'* rocked by turning the hand-wheel *k''* to drop the friction-wheel *K* upon the friction-wheel *i'*. This imparts a rapid motion to the screw *d* and, of course, to the sprocket-wheel upon the same shaft, and 110 through it to the forward shaft *d*, carrying the stay-log rapidly toward the rear of the machine. When it is passed back far enough, the wheel *K* is thrown up to the position shown 115 in Fig. 1, the exhausted flitch removed and a new one supplied. 120

It is obvious that the rack and its engaging pinion for actuating the offset may be replaced by a friction-wheel and plain track and also that other means may be employed to impart 125 a limited movement to the stay-log cross-feed. I have shown what I believe to be the simplest and best means to accomplish the objects above set forth, but consider all mere mechanical changes within the spirit and scope of my invention.

What I claim is—

1. In a veneer sawing machine, the combination of the supporting frame, the sliding carriage thereon, the stay log, the screws for feeding it transversely on the carriage, exteriorly screw threaded sleeves forming bearings for said feed screws, crank arms depending from said sleeves, screw threaded nuts 130

engaging the sleeves, said nuts being secured to the carriage, an actuating rod coupling the said crank arms together, and means such as shown, actuated by the movement of the carriage, to move the rod, to simultaneously rotate the feed screw bearings for the purpose of offsetting the stay log and bringing it back to its position as the carriage moves forward or backward, substantially as shown and described.

2. In a veneer sawing machine of the character described, the combination of the exteriorly screw threaded bearings for the stay log feed screws, the feed screws held against longitudinal movement within said bearings, the fixed nuts secured to the carriage to engage said screw threaded bearings, arms extending from said bearings, an actuating rod to couple said arms, means such as shown to limit the throw of the arms and connecting rod, a rack secured to the rear of the stationary frame or husk, stud journals projecting rearwardly from the base of the carriage, a pinion journaled upon one of said studs and meshing with the rack on the frame, a band pulley secured to the pinion and journaled upon the same stud, a band pulley journaled upon the other stud, an arm carried by said pulley and coupled to the connecting rod which works the screw threaded bearings of the feed screw, and the band passing over both pulleys, substantially as shown and described.

3. In a veneer sawing machine having the customary feed mechanism for the stay log, the exteriorly screw threaded bearings for the feed screws, having crank arms extending therefrom, nuts fixed to the carriage to engage the threads of said bearings, the feed screws journaled to turn in said screw threaded bearings but prevented from moving laterally therein, the connecting rod coupling the ends of the arms of the screw threaded bearings, buffers secured in the arms to strike against the fixed projection from the carriage and limit the movement of the arms in either direction, the rack, E, secured to the rear frame of the machine, the pinion, e, and fixed pulley, e², secured thereto, said pinion and pulley being journaled upon stud, e', projecting rearwardly from the carriage, the pulley, e³, journaled upon the stud projecting from the carriage, the arm, e⁴, secured to said pulley, extending therefrom and coupled to the connecting rod, and the band passing over

said pulleys, e² and e³, for the purpose of moving the connecting rod and simultaneously actuating the screw threaded bearings of the feed screws for the purpose of offsetting the stay log and returning it to its position, substantially as shown and described.

4. In a veneer sawing machine having the feed mechanism for the stay log, the combination of the carriage feed, a friction pulley thereon in addition to the friction pulleys for the feed, a pinion secured upon the rear feed screw journal, a rock shaft journaled in the rear upright standards of the carriage, a hand wheel on the forward end to rock the shaft, and a crank arm secured on the rear end of said shaft, a link carried by said crank arm, having a journal box at its free end, a journal extending through said box, a pinion secured upon one end of said journal to mesh with the gear wheel upon the feed screw shaft and a friction wheel secured upon the opposite end of said journal above the additional friction wheel secured upon the carriage feed shaft, whereby when said friction wheel is thrown down to engage said additional friction wheel, a rapid movement is imparted to the stay log feed screws and the stay log retracted, substantially as shown and described.

5. In a veneer mill of the character described, the combination of the rear feed screw for the stay log, a gear wheel, d⁶, secured upon the rear feed screw shaft, the rock shaft, K', journaled in bearings in the rear uprights of the carriage, the hand wheel, k³, secured upon the forward end of said shaft, the crank arm, k², secured upon the opposite end of the shaft, the link, k', carrying the box, k, in one end and at the opposite end pivoted to the crank arm, k², a friction wheel, K, secured upon one end of a journal which passes through the box, k, the pinion, k⁴, secured upon the opposite end and held in mesh with the gear wheel, d⁶, which is secured upon the feed screw, d, the friction gear, i', secured upon the driving shaft, i, immediately below the friction wheel, K, to rotate the wheel, K, when thrown down upon it, to impart a rapid movement to the stay log feed screws, for the purpose set forth.

EDWARD MYERS.
